CONVERSION PROCESS

Harrison C. Mayland, Chicago, Ill., assignor to
Universal Oil Products Company, Chicago, Ill.,
a corporation of Delaware

Application March 26, 1942, Serial No. 436,305

6 Claims. (Cl. 260—669)

This invention relates to a process for the conversion of organic materials and, more specifically, to the conversion of hydrocarbons.

The present invention is particularly applicable to the dehydrogenation of hydrocarbons. In view of the extreme importance at the present time of the production of styrene for use in connection with the manufacture of synthetic rubber, the present invention will be described in connection with the dehydrogenation of ethylbenzene for the production of styrene, although not with the intention of unduly limiting the invention.

Ethylbenzene, which is used as the charging stock to the present process, is produced in a number of ways. One of the preferred methods of manufacturing ethylbenzene is by the alkylation of benzene with ethylene in the presence of suitable catalysts, and particularly a solid phosphoric acid catalyst, as described in previously issued patents. Ethylbenzene may also be produced by dehydrocyclization of octanes or octylenes and is also produced in the catalytic reforming of gasoline or naphtha, and particularly when the reforming process is conducted in the presence of hydrogen in the type of process now known in the art as hydroforming. It is also produced in varying quantities during the cracking, and preferably the catalytic cracking, of higher boiling oils to produce gasoline.

The present invention includes a number of important features which are essential to a commercial process for the production of styrene from ethylbenzene. These various features will be described in detail in the following specification and claims.

One important feature of the present invention resides in the method of preliminarily separating the conversion products from the catalytic reactors. This step of the process comprises a two or three-stage flashing system which will hereinafter be described in detail.

Another feature of the present invention, as applied to the catalytic dehydrogenation of ethylbenzene, is the recycle of the unconverted ethylbenzene from the final separation zone back to the process for further conversion therein. Another feature is the use of relatively low pressures, preferably subatmospheric pressures, in the catalytic dehydrogenation reaction. These and other features of the invention will be hereinafter more fully described.

In one specific embodiment, the present invention relates to a process for the dehydrogenation of ethylbenzene to styrene which comprises subjecting said ethylbenzene to contact with a de-

hydrogenation catalyst under dehydrogenating conditions, separating the products of said dehydrogenation by flashing in two or more stages, employing substantially the same temperature and increasing pressures, finally separating the products of said conversion, and recycling the unconverted benzene to the process for further conversion therein. The accompanying diagrammatic drawing illustrates several specific methods 10 in which the present invention may be conducted but not with the intention of unduly limiting the same.

Referring to the drawing, ethylbenzene is introduced to the process through line 1 to pump 2, 15 by means of which it is directed through line 3 and pump 4 to process heater 5. The process heater may comprise any suitable apparatus, by means of which the ethylbenzene is heated to the desired temperature which may range from about 20 1000° F. to about 1200° F. The products from heater 5 are directed through line 6 into catalytic reactors 7 and 8.

Although illustrated in the drawing as comprising two reactors, it is understood that the 25 process may employ one or three or more catalytic reactors. Usually the reactors are employed in multiples of two so that one or any number thereof may be undergoing processing while the catalyst in the other one or any number thereof 30 may be undergoing regeneration.

The particular catalyst employed in the process will depend upon the reaction desired. For example, in the dehydrogenation of ethylbenzene to styrene, any satisfactory dehydrogenation 35 catalyst may be employed. A suitable catalyst includes alumina, magnesia, or other suitable refractory oxides composited with a compound, and preferably an oxide, of the elements in the left-hand columns of groups IV, V, and VI of the 40 periodic table. One of the preferred catalysts comprises alumina composited with chromia. It is understood that these or other catalysts will not entirely be equivalent in their activity and that the conditions of operation will be modified 45 accordingly.

Assuming that catalytic reactor 7 is being used for processing, the heated ethylbenzene will be directed through line 9, valve 10, line 11 and line 12 into catalytic reactor 7. The heated products are introduced into the reactor at a relatively low pressure, which pressure may range, for example, from 1½ pounds absolute up to 20 pounds absolute. Usually a subatmospheric pressure of about 5 pounds absolute is preferred. Liquid hourly space velocities employed range from 0.5

to 8. The liquid hourly space velocity is defined as the volume of liquid charging stock per hour per unit volume of catalyst. It is understood, of course, that the temperature, pressure and space velocity employed will be correlated to effect the desired reactions.

Since the dehydrogenation reaction is endothermic, it will be necessary to furnish sufficient heat to maintain the desired reaction. One suitable method includes the use of substantially adiabatic operations, in which case either the charging stock is heated to a sufficiently high temperature or a heated extraneous material is introduced with the charging stock to supply the heat of reaction. Another suitable method is illustrated in the drawing, which comprises passing a heat convective medium in indirect heat exchange with the products undergoing conversion. In this type of operation a tubular heat exchanger type reactor may be employed and preferably is designed for a low pressure drop. The catalyst is usually disposed within the tubes and a suitable convective medium is passed through the space surrounding the tubes. Another suitable type of reactor is of the form illustrated and described in United States Patent No. 2,252,719. The heat convective medium may comprise either normally gaseous, liquid or solid material. One suitable material includes a molten salt, which salt is circulated in large quantities through the space surrounding the catalyst sections. Referring to the drawing, the heat convective medium is introduced to reactor 7 through line 13 and removed therefrom through line 14.

The conversion products from reactor 7 are withdrawn therefrom through line 14' and passed through steam generator 15, line 16, process cooler 17, into line 18. It is understood, of course, that any other suitable means of cooling the hot conversion products to the desired temperature may be utilized. One convenient means includes passing the fresh and/or recycled ethylbenzene in indirect heat exchange with the products from reactor 7, either by the use of cooler 17 or by any other suitable type of exchanger. It is also within the scope of the invention to omit steam generator 15 when desired.

While reactor 7 is being utilized for effecting the dehydrogenation reaction, the catalyst in reactor 8 is being regenerated. Regeneration is accomplished by burning the carbonaceous material from the catalyst with flue gases containing the required amount of oxygen. This system usually comprises purging the reactors with oxygen free gases before and after the burning operation. The regeneration gases are supplied through line 19, line 20, valve 21, line 22 and line 23 into contact with the catalyst and the regeneration gases therefrom are passed through line 24, steam generator 25, line 26, process cooler 27 into line 28. Likewise, steam generator 25 and process cooler 27 may be modified in the same manner as heretofore described in connection with steam generator 16 and process cooler 11. Manifold line 29, valve 30, line 31, as well as line 32, valve 33 and line 34, are utilized when it is desired to switch the processing and catalyst regeneration cycles between reactors 7 and 8.

While the catalyst in reactor 8 is undergoing regeneration, heat is liberated due to the exothermicity of the reaction, and it will be necessary to cool the same in order to avoid excessive temperatures which may prove detrimental to the catalyst. The cooling of reactor 8 may be accomplished in a similar manner as that described

in connection with the heating of reactor 7. A particularly suitable method includes the circulation of a molten salt which may be accomplished by passing the same through line 35 into the space surrounding the catalyst-containing tubes in reactor 8 and removing the molten salt through line 36.

The arrangement of the outlet switch valves is substantially the same as the inlet switch valves heretofore described. The conversion products from reactor 7 are passed through line 18, line 37, valve 38, line 39, line 40, and line 41 to the preliminary separation system. The regenerating gases from reactor 8 are passed through line 28, line 42, valve 43, line 44, and line 45' to a suitable recovery system. When reactors 7 and 8 are switched as regards the processing and catalyst regeneration, regenerating gases would be supplied to reactor 7 in the manner heretofore described and would be removed through lines 14', 16 and 18, and then directed through line 45, valve 46, line 47, into and through line 45'. At the same time, the dehydrogenation conversion products would be passed through lines 24, 26 and 28 through line 48, valve 49, line 50, into and through lines 40 and 41.

The products passing through line 41 contain unconverted ethylbenzene, styrene, some toluene and benzene, a higher boiling residue, and light gases. An important feature of the present invention is the method to be presently described for the preliminary separation of these products. Both styrene and ethylbenzene are relatively expensive products and their recovery to the greatest extent is of importance. This is accomplished according to the features of the present invention.

The conversion products in line 41 are preferably cooled by the means heretofore described to a temperature within the range of 50° F. to 200° F. and usually about 100° F. Reactors 7 and 8, steam generators 15 and 25, process coolers 17 and 27, pipe lines and switch valves are preferably designed so as not to effect too great a pressure drop in order that the conversion products may be introduced to the first flash drum at substantially the same or only a slightly modified pressure to that utilized in the catalytic reactors.

50 The conversion products are passed through line 41 into flash drum 51. In flash drum 51 a rough separation of the products introduced thereto is accomplished. The liquified products will contain a major portion of the unconverted ethylbenzene, styrene and higher boiling residue. The liquified products are removed from flash drum 51 through line 52 to pump 53, by means of which they are directed through line 54 into separation zone 55.

60 The non-condensed products from zone 51 are withdrawn through line 55' and directed to compressor 56, by means of which they are raised to a pressure of between about atmospheric and about 50 pounds superatmospheric and directed through line 57 and cooler 58. In cooler 58 the products are cooled to the desired temperature, which may range from about 50° F. to about 200° F., and the cooled products are then directed through line 59 into flash drum 60.

65 In flash drum 60 an additional separation of the conversion products is effected. The condensed products are withdrawn therefrom through line 61 to pump 62, by means of which they are directed through line 63 into line 54.

70 75 In one embodiment of the invention, particu-

larly when the uncondensed products withdrawn from zone 60 contain substantially no, or relatively minor proportions of, ethylbenzene or styrene, the non-condensed vapors may be withdrawn from zone 60 through line 64 and discharged from the system. However, in another embodiment of the invention, particularly when this portion contains a sufficient quantity of ethylbenzene and styrene to economically justify their further recovery, the non-condensed products withdrawn from zone 60 may be directed through line 65 to compressor 66, by means of which they are raised to a pressure of between about 50 and about 200 pounds or more, and then directed through line 67 to cooler 68. The products in passing through cooler 68 are cooled to the desired temperature, which may range from between about 50° F. and about 200° F., and are then passed through line 69 into flash drum 70.

The products introduced into flash drum 70 will comprise a large proportion of normally gaseous material and a minor proportion of normally liquid material. This has the tendency of dissolving some of the normally gaseous material in the normally liquid material and, as a particular feature of the present invention, an absorption oil is commingled with the compressed products in line 67. Alternatively, the absorption oil may be commingled with the compressed products after cooler 68, if desired. The absorption oil in this step of the process serves to absorb the remaining minor quantities of ethylbenzene and styrene and at the same time absorbs some of the lighter gases. Any suitable absorption oil may be used in this step of the process, the major requirement being that the absorption oil will not vaporize and be withdrawn with the gaseous products under the conditions of operation maintained in zone 70. The unabsorbed and uncondensed lighter products are withdrawn from zone 70 through line 71 to storage or elsewhere, as desired.

The liquid products are withdrawn from zone 70 through line 72 to pump 73, by means of which they are directed through line 74 and line 41 into flash drum 51. In flash drum 51 any of the lighter gases absorbed in the absorption oil are flashed off and withdrawn through line 55', while the liquid products are withdrawn through line 52 and directed into the final separation step of the process.

Zone 55 may comprise any suitable type of process to effect the desired separation between the styrene and other products introduced thereto. Since no novelty is claimed herein for the separation step as such, there appears no need for a detailed recitation thereof in the present application. Whichever process is used in zone 55, the products introduced thereto are separated into normally gaseous products, benzene and toluene, either together or separately, unconverted ethylbenzene, styrene, and a higher boiling residue. The normally gaseous products will comprise a very minor per cent of the products introduced into zone 55, and this greatly facilitates the subsequent separation and recovery of styrene and ethylbenzene. This is one of the important advantages of the flashing system heretofore described. The normally gaseous products are removed from zone 55 through line 75 to storage or elsewhere, as desired. Benzene and toluene may be separately recovered or recovered in admixture and withdrawn from the process through line 76 to storage or elsewhere, as desired. Since benzene and/or toluene are satisfactory for use

as the absorption oil heretofore mentioned, it is within the scope of the invention to direct all or a portion of the separated benzene and/or toluene through line 77 to pump 78, by means of which it may be directed through line 79, 80, 67, and 69 to flash drum 70 for use therein as heretofore described.

Unconverted ethylbenzene is withdrawn from zone 55 through line 81 and all or a portion is withdrawn from the process. Preferably, however, at least a portion of the ethylbenzene is recycled by way of line 81', pump 82, line 83, and line 3 to heater 5 and reactors 1 and 8. A higher boiling residue is withdrawn from zone 55 through line 85 and may be removed from the process. Since this material also appears satisfactory for use as the absorption oil, at least a portion thereof may be directed through line 86 to pump 87, by means of which it may be directed through lines 88, 89, and 80 to flash drum 70. In case it is desired to use all or a portion of the absorption oil from an extraneous source, the absorption oil may be introduced to the process by way of line 90, pump 91, into lines 89 and 80, to flash drum 70.

In another embodiment of the invention, particularly when an absorption oil is not utilized, the liquid products from flash drum 70 may be directed through lines 74, branch line 92, and line 54, into separation zone 55.

The following examples are introduced for the purpose of further illustrating the invention and not with the intention of unduly limiting the same.

Ethylbenzene is dehydrogenated in the presence of an alumina-chromia catalyst at a temperature of about 1100° F., an outlet pressure of about 5 pounds absolute, and liquid hourly space velocity of about 2.3 to effect conversion of about 40% by weight of ethylbenzene per pass to yield an ultimate production of 91% weight of styrene based upon the ethylbenzene converted. The dehydrogenation conversion products are introduced to flash drum 51 at a temperature of about 100° F. and a pressure of about 5 pounds absolute. The liquid and non-condensed products are separated, the liquid products being directed to separation zone 55, while the non-condensed products are compressed to a pressure of about 25 pounds absolute or 10 pound gauge, cooled to a temperature of about 100° F. and introduced into flash drum 60. The liquid products are separated from the non-condensed products, the liquid products being directed into separation zone 55, while the non-condensed products are compressed to a pressure of about 125 pounds absolute, commingled with an absorption oil, cooled to a temperature of about 100° F. and introduced into flash drum 70. The process gas is withdrawn from the upper portion of zone 70 and contains substantially no, or perhaps only minute quantities of, ethylbenzene or styrene. The liquid products withdrawn from flash drum 70 are returned to flash drum 51 and any absorbed gases are separated in this zone, while the normally liquid products, including the ethylbenzene and styrene, are withdrawn from the lower portion of this zone and are supplied to final separation zone 55.

In the other embodiment of the invention, in which an absorption oil is not utilized, the process is conducted substantially as set forth in the preceding paragraph with the exception that the liquid products from flash drum 70 are com-

mingled with the liquid products withdrawn from flash drums 51 and 60 and the commingled liquid products are directed to separation zone 55. In this embodiment of the invention minor quantities of ethylbenzene and styrene are withdrawn with the process gases from the upper portion of flash drum 70. This embodiment of the invention may be preferred when difficulty is encountered in zone 55 in the final separation of styrene from the other products. The particular flashing system to be employed will thus depend in part upon the particular final styrene separation process employed.

I claim as my invention:

1. A process for separating the conversion products formed in the dehydrogenation of ethylbenzene under subatmospheric pressure which comprises cooling the products of said dehydrogenation, introducing the cooled products into a first separation zone at substantially the same pressure as employed in said dehydrogenation, separating condensed from uncondensed materials in said first separation zone, withdrawing the uncondensed materials from said first separation zone and compressing the same to a higher pressure and introducing the compressed materials into a second separation zone, separating condensed from uncondensed materials in said second separation zone, withdrawing the latter from said second separation zone and compressing the same to a higher pressure, commingling an absorption oil with the compressed materials from said second zone and introducing the same to a third separation zone, separating uncondensed and unabsoed materials from the condensed and absorbed materials in said third separation zone, withdrawing the former from the process and introducing the condensed and absorbed materials into said first separation zone, withdrawing the liquid products from said first separation zone and commingling the same with

the condensed materials withdrawn from said second separation zone, and separating styrene and unconverted ethylbenzene from the commingled materials.

5. 2. A process such as defined in claim 1, wherein in said absorption oil comprises benzene which is recovered during the separation of the said unconverted ethylbenzene and styrene.

10 3. A process such as defined in claim 1, wherein said absorption oil comprises toluene which is recovered during the separation of the said unconverted ethylbenzene and styrene.

15 4. A process such as defined in claim 1, wherein in said absorption oil comprises benzene and toluene which are recovered during the separation of the said unconverted ethylbenzene and styrene.

20 5. A process such as defined in claim 1, wherein in said absorption oil comprises material boiling higher than styrene, which higher boiling material is recovered during the separation of said ethylbenzene and styrene from the other products of the process.

25 6. A process for separating the conversion products formed in the dehydrogenation of ethylbenzene to styrene, which comprises cooling said products and separating condensed from uncondensed materials in a first zone, compressing the uncondensed materials and separating resultant liquid from the remaining gaseous products in a second zone, commingling an absorption oil with the gaseous products from said second zone to absorb components of the latter in the former, introducing the thus enriched absorption oil to 30 said first zone to remove absorbed light gases therefrom, supplying the liquid materials from said first and second zones to an additional separating zone and therein separating styrene, unconverted ethylbenzene and absorption oil from 35 the commingled materials.

HARRISON C. MAYLAND.
